UNITED STATES PATENT OFFICE.

LOREN L. WHITNEY, OF HAMMOND, INDIANA, ASSIGNOR TO AMERICAN STEEL
FOUNDRIES, OF CHICAGO, ILLINOIS, A CORPORATION OF NEW JERSEY.

METHOD OF FORGING BRAKE-BEAM TRUNNIONS.

Application filed April 28, 1920. Serial No. 377,156.

To all whom it may concern:

Be it known that I, LOREN L. WHITNEY, a citizen of the United States, residing at Hammond, in the county of Lake and State 5 of Indiana, have invented certain new and useful Improvements in Methods of Forging Brake-Beam Trunnions, of which the following is a specification.

This invention relates to a method for 10 forging brake beam trunnions.

An object of this invention is to simplify 15 and improve the methods of forging brake beam trunnions, reducing the cost of manufacture and at the same time providing a brake beam trunnion adapted to meet the requirements for successful commercial use.

This and other objects are accomplished 20 by means of the method disclosed on the accompanying sheet of drawings, in which—

Figures 1 and 2 are end and top plan 25 views, respectively, of a brake beam blank;

Figures 3 and 4 are end and top plan views of the same blank after being upset;

Figures 5 and 6 are end and top plan 30 views of the same blank after being further upset;

Figures 7 and 8 are end and top plan 35 views of the blank after being still further upset, the blank now being shown as provided with sufficient built-up stock necessary for succeeding operations;

Figures 9 and 10 are end and top plan 40 views of the blank after the end has been drawn out a predetermined amount under a steam hammer between suitable dies;

Figures 11 and 12 are end and top plan 45 views of the same blank after the end of the blank has been subjected to pressure between dies of a drop hammer to its completed form, with the exception of the fin; and

Figures 13 and 14 are end and top plan 50 views showing the brake beam trunnion in finished form.

It will be noted from the figures of the 55 drawings that only a portion of the brake beam has been shown, it being understood that the opposite end of same will appear as the end shown.

The type of brake beam shown is of the

plain I section. In forming the trunnion a 50 commercial brake beam blank 10 of I section is provided, as shown in Figures 1 and 2. The end of the blank is then heated and upset a predetermined amount in any suitable well-known type of upsetting machine, 55 giving the end of the blank an appearance as shown in Figures 3 and 4. The end of the blank is then upset an increased amount as shown in Figures 5 and 6, and then subjected to a third upsetting action, giving 60 the end of the blank a built-up portion 11 of stock, as shown in Figures 7 and 8, preparatory to the succeeding operations. It will be understood that during all of these upsetting actions the blank 10 is properly gripped 65 between suitable dies to control the upsetting at the proper points. The end of the beam is then drawn out under a steam hammer between suitable dies to the form shown in Figures 9 and 10, giving the trunnion 70 portion 12 its first rounded appearance. The trunnion portion is then subjected to pressure between the dies of a drop hammer, giving the trunnion an appearance as shown in Figures 11 and 12, there being a fin or 75 flash 13 formed around the trunnion and between the adjacent portions of the cooperating dies. The fin or flash is then removed, leaving the brake beam trunnion 14 in its finished form, as shown in Figures 13 and 80 14, the trunnion being provided with a shoulder 15.

It is my intention to cover all modifications of the invention falling within the spirit and scope of the following claim. 85

I claim:

The method of forming a brake beam trunnion, consisting in providing a blank, heating said blank, upsetting same to build up the stock for the trunnion, drawing out 90 the built-up portion to approach the final trunnion shape, and subjecting said drawn-out portion to a further drawing-out action between dies to give the trunnion its final shape. 95

Signed at Hammond, Indiana, this 22 day of April, 1920.

LOREN L. WHITNEY.
